Germany, a corporation of Germany

Application October 29, 1957, Serial No. 693,075

Claims priority, application Germany June 25, 1957

7 Claims. (Cl. 137—622)

My present invention relates to a hydraulic distributor for power lifters and the like and has for its principal object the provision of improved means for selectively controlling the flow of a motive fluid to a number of discharge ports and for varying the operating pressure of the fluid.

Known distributors for hydraulic hoists, adapted to be used on tractors or similar equipment, are set to a predetermined operating pressure and, therefore, must be employed together with separate valve means to vary the pressure of the conveyed fluid. Accordingly, these prior-art arrangements are relatively complex, occupy considerable space and, owing to the independent actuation of their controls, require a great deal of attention from the operator; avoidance of these drawbacks is, therefore, another object of my invention.

A further object of the invention is to provide a distributor of the character set forth above which is simple, compact in form and size, and adapted to be manufactured as a standard article for use with many types of hydraulic apparatus.

A still further object of the invention is to provide a distributor having means for selectively switching a source of motive fluid from one discharge port to another and for simultaneously varying the pressure of said fluid.

A hydraulic distributor according to a preferred embodiment of the instant invention has a tubular casing provided with an intake port and a plurality of discharge ports, and a hollow valve member in the form of a sliding piston with an axial bore and transverse apertures which, upon suitable axial and/or angular displacement in the casing, may be brought into a position to permit or prevent passage of fluid from the intake port through the piston and into selected discharge ports. A single operating member is provided for selectively placing one or more piston apertures in communicative position with respect to the intake and discharge ports in the casing, and a safety valve is installed directly in the sliding piston in such manner that a predetermined (e.g. axial) displacement of the piston automatically brings about a concurrent adjustment of the safety valve to a higher or a lower operating pressure.

The discharge ports through which the fluid at higher or lower pressures is permitted to leave the casing in different positions of the piston may be connected either to the same or to different loads, such as hydraulic jacks or further distributors connected in tandem with the first one, depending on whether it is desired to actuate a single controlled device or a plurality of such devices at different operating pressures.

The invention will be described in greater detail with reference to the accompanying drawing in which:

Fig. 1 is a longitudinal axial section, taken on line 1—1 of Fig. 5, through a distributor embodying the invention;

Fig. 2 is a similar sectional view of the distributor, showing its piston in a different axial position;

Fig. 3 is a transverse section taken on line 3—3 of Fig. 1 with the valve piston turned through about 45 degrees;

Fig. 4 is a transverse section taken on line 4—4 of Fig. 2 with the piston rotated through another 45 degrees; and

2

Fig. 5 is an enlarged right-hand end view of the distributor showing two additional operative positions of the piston-actuating member in dot-dash lines.

In Figs. 1 and 2 there is shown a tubular casing 11 which is fixed to a supporting wall 10 by means of four bolts 12, the latter also holding a square retaining frame 13. The frame 13 serves as a bearing for a hub 14 whose slot 14a accommodates an actuating lever 15 swingable about a pivot 16. The bifurcate lower end of lever 15 straddles a pin 17 which spans the slotted end 18a of a piston 18, the latter being slidably received in the bore 11a of the valve casing in such manner as to permit axial displacement of the piston when the lever 15 is swung about pivot 16, between the limiting positions shown in Figs. 1 and 2, as well as angular displacement of the piston upon rotation of lever 15 between a normal working position and several alternative positions shown at 15', 15'' (dot-dash lines) in Fig. 5, the hub 14 rotating with the piston. The extent of axial displacement of the piston in the direction of arrow A (see Fig. 1) is controlled by a ring 19 which abuts against a sealing ring 59, a radial shoulder 20 determining the extent of axial movement of the piston in the opposing direction of arrow B (see Fig. 2). A stud 21, projecting from the hub 14, controls the extent of angular movement of the piston in the direction of arrow C (Figs. 4 and 5) by abutting against suitable stops, one of which is shown at 22 in Fig. 5. Conventional indexing means comprising a ball 23 and a spring 24 prevent unintentional rotation of the hub 14 with respect to the valve casing 11, and a similar detent comprising a ball 25 and a spring 26 is provided in a tubular member 27 on the hub 14 (see Fig. 5) for the purpose of frictionally holding the piston against undesirable axial displacement.

Piston 18 has an axial bore 28 which is open at one end and communicates with the interior 11a of casing 11 via entrance apertures 29a, 29b. In Fig. 1, the aperture 29a is shown in communication with the intake port 30 provided in the casing 11. Port 30 is connected with a source (not shown) of fluid under pressure, such as a hydraulic pump drawing from an oil sump, whereby such fluid is free to pass through inlets 30 and 29a into the piston bore 28 and thence through exit apertures 31, 32 in the piston and aligned discharge ports 33, 34 in the casing to respective controlled devices designated in the drawing as Load I and Load II. In this position of the piston, its second pair of exit apertures 35, 36 are offset from discharge ports 37, 38 in the valve casing, the latter two ports being respectively connected with Load II (in parallel with port 33) and with a further controlled device designated as Load III. When the piston 18 is moved in the direction of arrow B into the position of Fig. 2, the casing 11 closes the apertures 31, 32 while the fluid is free to pass through aligned outlets 35, 37 and 36, 38. It will be noted that peripheral cutouts 29a', 29b' in communication with apertures 29a, 29b permit entry of the fluid into piston-bore 28 in and between both extreme axial positions of the piston. The flow of fluid into the bore 28 may be reduced or fully cut off upon rotation of lever 15 in the direction of arrow C whereby the inlets 29a, 29b are closed by casing 11 and the piston-bore 28 communicates with the oil sump through an enlarged cutout 51 on piston 18 and a discharge port 39 provided in the casing (see Figs. 3 and 4).

Piston 18 also carries a pressure-regulating valve 40 comprising a sleeve 41 held in place in the enlarged open end of piston bore 28 by a tubular plug 42. Sleeve 41 defines an axial channel 43 slidably receiving a valve rod 44 whose perforated head 44a is urged toward the inner (right-hand) end of this channel by a spring 50 within plug 42. Lateral openings 45a, 45b and 46a, 46b in the sleeve 41 are in permanent communication with respective

relief orifices 47a, 47b and 48a, 48b in the piston 18. The enlarged left-hand end 44b of the valve rod 44 abuts against a sliding bolt 49a which forms the movable anchor of spring 50, its other anchor being a fixed stud 49b. In the position of Fig. 1, the reduced portion 44c of the valve rod 44 is out of register with openings 45a, 45b, 46a, 46b as the rod occupies its extreme position corresponding to the lowest pressure of fluid in the piston bore 28; thus, the safety valve 40 is closed and no fluid can escape through any of orifices 47a, 47b, 48a, 48b until the pressure within piston bore 28 has risen sufficiently to align the portion 44c with the right-hand valve openings 45a and 45b. In Fig. 2, with the piston 18 withdrawn to the right to have the casing 11 obstruct the orifices 47a and 47b, the spring 50 is almost totally compressed under still higher fluid pressure and the fluid is free to flow through the perforated head 44a, around the reduced portion 44c of the valve rod and thence through the aligned passages 46a, 48a and 46b, 48b back to the oil sump. Thus, the lever 15 controls the safety valve 40 and hence the fluid pressure in piston bore 28 simultaneously with the selection of outlets in the valve casing 11 to lead the fluid toward certain controlled devices (Loads I and II) under relatively low pressure, e.g., of 75 atmospheres, and toward the same or other devices (Loads II and III) under relatively high pressure, e.g., of 100 atmospheres.

Safety valve 40 will also operate when the lever 15 is in an axial position intermediate those shown in Figs. 1 and 2 while occupying the angular position shown in full lines in Fig. 5, all the discharge ports in the distributor casing 11 being then closed.

Fig. 3 shows the piston 18 turned through about 45 degrees in the direction of arrow C. Actuating lever 15 is then in the position 15' (see Fig. 5). Cutout 51 communicates with the discharge port 39 which leads the fluid back to the oil sump. Upon further rotation of the lever in the same direction into its position 15" shown in Fig. 5, longitudinal grooves 53, 54 on the periphery of piston 18 together with cutouts 51, 52 provide a path from either or both pairs of discharge ports 33, 34 and 37, 38 to the central port 39 (see Fig. 4) to permit the return of fluid from the associated loads to the oil sump. The triangular cross-sections of the grooves 53, 54 permit flow control between these ports through variation of the effective width of the fluid path by slightly rotating the piston 18. By turning the lever 15 back into the position shown in full lines in Fig. 5, i.e., into the position of Figs. 1 and 2, the cutouts 51, 52 are closed by the casing 11 and the distributor may supply fluid to the discharge ports 33, 34 or 37, 38 upon axial displacement of the piston to the left or to the right, respectively, in the previously described manner.

It will thus be seen that I have provided a device for the channeling of oil or some other hydraulic fluid over a plurality of different paths into and out of the interior of a valve member, represented by piston 18 in the embodiment specifically described, the shift from one operating position to another being accompanied in certain instances by the blocking or the unblocking of a pressure-relief orifice (such as the one indicated at 47a) in order to vary the critical pressure at which the safety valve 40 will open. If the orifices 48a and 48b were omitted, then the safety valve would be completely disabled in the axial piston position of Fig. 2. Moreover, this change-over in the response threshold of the safety valve need not necessarily coincide with a switching operation, as has been particularly illustrated for Load II which in either of the positions shown in Figs. 1 and 2 will receive fluid via intake port 30 and discharge port 33 or 37, the latter two ports effectively constituting a single outlet in view of their interconnection by a common discharge duct shown in dot-dash lines at 55. The rotatability of the piston, on the other hand, enables the selective closing and/or opening of fluid paths with-

out any readjustment in the mode of operation of the safety valve.

My invention is, of course, not limited to the various structural and operational details specifically disclosed herein but may be embodied in numerous modifications and adaptations without departing from the spirit and scope of the appended claims.

I claim:

1. A distributor for a motive fluid under pressure, comprising a casing, a hollow valve member displaceably mounted in said casing, actuator means for displacing said valve member between a first and a second operating position, inlet means on said casing and on said valve member for admitting fluid into said valve member in each of said operating positions, and outlet means on said casing and on said valve member for discharging said fluid from the interior of said valve member in at least one of said positions; said valve member being provided with safety means including a portion of said member provided with a plurality of pressure-relief orifices, blocking means on said casing positioned to obstruct one of said orifices in said second position but not in said first position, and spring-loaded closure means in said valve member normally stopping the flow of fluid from said interior through said orifices, said closure means being adapted to yield under increasing fluid pressure for progressively uncovering first said one and then the other of said orifices whereby the fluid will be allowed to escape from said interior by way of said safety means at a relatively low pressure in said first operating position and at a relatively high pressure in said second operating position of said valve member.

2. A distributor according to claim 1, wherein said valve member is an axially slidible piston, said orifices being axially spaced on said piston.

3. A distributor according to claim 2, wherein said piston is provided with an extremity projecting from said casing, said one orifice being withdrawn into said casing in said second operating position.

4. A distributor according to claim 2, wherein said outlet means comprises a plurality of angularly spaced discharge ports on said casing and at least one exit aperture on said piston, said piston being selectively rotatable in said casing under the control of said actuator means into a plurality of angular positions in which said exit aperture registers with respective ones of said discharge ports.

5. A distributor according to claim 2, wherein said outlet means comprises a plurality of axially spaced discharge ports on said casing and at least one exit aperture on said piston, said piston being selectively rotatable in said casing under the control of said actuator means into a plurality of angular positions, said exit aperture registering with one of said ports in one of said angular positions and with both of said ports in another of said angular positions.

6. A distributor according to claim 2, wherein said outlet means comprises a plurality of axially spaced discharge ports on said casing and a peripheral groove on said piston, said piston being axially and angularly displaceable by said actuator means into a position in which said groove bridges said discharge ports.

7. A distributor according to claim 6, wherein said groove is of tapering cross-section, thereby establishing between said discharge ports a path of different effective width in different angular positions of said piston.
